UNITED STATES PATENT OFFICE.

FRANCIS W. MALLETT, OF NEW HAVEN, CONNECTICUT, ASSIGNOR TO COOK AND PORTER NEEDLE COMPANY, OF BOSTON, MASSACHUSETTS.

IMPROVEMENT IN MACHINES FOR GRINDING NEEDLES.

Specification forming part of Letters Patent No. 172,639, dated January 25, 1876; application filed July 13, 1875.

To all whom it may concern:

Be it known that I, FRANCIS W. MALLETT, of New Haven, in the county of New Haven and State of Connecticut, have invented a new Improvement in Needle-Machines; and I do hereby declare the following, when taken in connection with the accompanying drawings and the letters of reference marked thereon, to be a full, clear, and exact description of the same, and which said drawings constitute part of this specification, and represent, in—Figure 1, plan or top view; Figs. 2, 3, 4, 5, 6, 7, detached views.

This invention relates to the construction of a machine for the manufacture of that class of sewing-machine needles in which the body of the needle is reduced from the shank, the object of the invention being to present the needles to, and rotate them in their passage over, the longitudinal surface of a grinding-cylinder; and the invention consists in the mechanism hereinafter described, and recited in the claims.

A is the bed-plate of the machine; B, the driving-shaft arranged in suitable bearings B', and caused to revolve by the application of power thereto in any known or convenient manner. C is the bed or way on which the needle-blanks are laid. Upon this bed plates D D' are arranged, and so as to be longitudinally guided on the surface of the said bed.

These plates are constructed with a series of transverse notches, *a*, upon their forward edge, the said notches corresponding in width to the diameter of the needle-shanks, or slightly larger, and the ends of the plates are formed with a dovetail or other convenient connection, so that one end of one plate may be readily attached to or detached from the corresponding end of the other, and they are caused to move longitudinally on the bed C by means of a worm, E, driven from the shaft B, and working in corresponding teeth on the rear edge of the said plates, as seen in Fig. 1.

Above these plates is a reciprocating plate, F, (see Figs. 1 and 4,) the reciprocating motion being imparted to it by a crank, F', from the driving-shaft, as seen in Figs. 1 and 3. This reciprocating plate is above the bed

C a distance equal to or slightly less than the diameter of the needle-shank, and the plate extends over the notches *a* in the plates D, as seen in Figs. 1 and 4.

Directly beneath the reciprocating plate F there is a corresponding reciprocating plate, C¹, (see Fig. 2,) and which is in the same plane, or flush with the surface of the bed C. The reciprocating movement is imparted to this plate C¹ by means of a lever, C², its lower end in connection with a projection, F², from the reciprocating plate F, the upper end in connection with the plate C¹, and with an intermediate stationary fulcrum, d, as seen in Figs. 3 and 4, so that the movement of the plate F will impart a corresponding movement to the plate C¹, but in the opposite direction; hence the needle-shanks lying between these two oppositely-reciprocating plates will be rotated back and forth, corresponding to such reciprocating movement of the plates F and C¹, and at the same time the traversing plates D will carry the needle-blanks along between the plates, so that they advance while they are so rotated. In front of the bed C there is arranged an adjustable guide, G, distant from the rear end of the notches in the plates D equal to the length of the needle-blanks, and so as to prevent longitudinal movement of the blanks. In front of the reciprocating plates F and C¹ the grinding-cylinder L is arranged and caused to revolve rapidly by the application of power thereto in any convenient manner. This cylinder is substantially parallel with the plates F and C¹, and is arranged on a carriage, L², the said carriage constructed so as to be moved transversely between suitable guides L³, and a reciprocating movement is imparted to the carriage by a crank, L¹, on the driving-shaft, so as to move the cylinder toward and from the reciprocating plates F and C¹, and above the cylinder there is arranged a pressure-bar, P, made adjustable relatively to the longitudinal surface of the cylinder, but so as to move with the carriage toward and from the reciprocating plates, and so that the cylinder will pass below the needle-blanks and the pressure-bar above.

The needle-blanks are laid into the notches—say, in the plate D'—and the machine put in

motion. These blanks will be carried between the reciprocating plates F and C¹, and there receive a rotative movement, while at the same time the grinding-cylinder will pass beneath the several blanks, commencing the grinding so soon as the blanks arrive upon the cylinder, and continuing it until the blanks are carried off the opposite end, thereby gradually grinding the blanks until they are reduced to the required size, and to insure such regular reduction the pressure-bar P should be set at the last grinding end of the cylinder, distant from the cylinder only the diameter of the finished blank.

As the plates D D' pass through beyond the opposite end of the reciprocating plates they are removed and reset at the other end to take new blanks, the finished blanks being thereby discharged from the machine.

It will be understood that the advance of the grinding-cylinder toward the reciprocating plates is so far as to grind the blanks up to the shanks. By this construction it is only necessary to introduce the blanks at one end of the machine and they pass out completely shaped at the other end.

To facilitate the rotation of the blanks, it may be desirable to coat the working-surface of the reciprocating plates with leather or other substance, which will produce a greater friction than the metal itself.

The adjustment of the different parts of the machine, for different sizes or grades of work, will be readily understood by those familiar with similar machines.

While I prefer to make the notched plates detachable one from the other, it will be evident that these may be used in the form of a band, and have a continuous movement, and the same result be obtained. These detachable notched plates are applicable to carrying blanks, whether they be rotated or not, for presenting the blanks for other parts of the

work, as for grooving, eye-punching, &c., or to other machines in which a progressive feed is desirable.

The plates for rotating the blanks are both represented, and thus far described, as revolving, and while this is preferred, one may be stationary and the other reciprocating, and give the required rotation of the blanks.

The machine may be used for pointing the needles, and in that case the grinding-cylinder would not necessarily have the reciprocating movement described, and in that case the pressure-bar may also be dispensed with. A hopper may be applied for feeding the blanks to the notches, if desirable.

Having thus fully described my invention, what I claim as new, and desire to secure by Letters Patent, is—

1. The herein-described feeding device for needles and other machines, consisting of the notched detachable plates, combined with mechanism substantially such as described, to impart a progressive movement to said plates, substantially as set forth.

2. In combination with the notched carrying-plates, and a grinding-cylinder, a pair of plates, F and C¹, one or both of which has a reciprocating movement, substantially as described.

3. The combination of the notched carrying-plates, a grinding-cylinder, a pair of plates, F and C¹, one or both of which has a reciprocating movement, and the adjustable guide G, substantially as described.

4. In combination with a pair of reciprocating plates, F and C¹, and a grinding-cylinder, the traversing notched carrying-plates, and the adjustable pressure-bar P, substantially as described.

FRANCIS W. MALLETT.
